Primary Examiner — Sanjeev Paul

(74) Attorney, Agent, or Firm — Duane Morris LLP

(57) **CLAIM**

The ornamental design for a hinge for eyeglasses as shown and described.

DESCRIPTION

FIG. 1 is a perspective view of a hinge for eyeglasses; FIG. 2 is a front view thereof; FIG. 3 is a back view thereof; FIG. 4 is a right side view thereof; FIG. 5 is a left side view thereof; FIG. 6 is a top view thereof; FIG. 7 is a bottom view thereof; FIG. 8 is a perspective view of a hinge for eyeglasses in another example of the design;

(Continued)

FIG. 9 is a front view thereof;
 FIG. 10 is a back view thereof;
 FIG. 11 is a right side view thereof;
 FIG. 12 is a left side view thereof;
 FIG. 13 is a top view thereof; and,
 FIG. 14 is a bottom view thereof.
 The broken lines represent unclaimed subject matter and
 form no part of the claimed design.
